UNITED STATES PATENT OFFICE.

WILLARD IRVING TWOMBLY, OF NEW YORK, N. Y., ASSIGNOR TO TWOMBLY MOTORS COMPANY, OF NEW YORK, N. Y., A CORPORATION OF NEW YORK.

INTERNAL-COMBUSTION ENGINE.

1,047,860.

Specification of Letters Patent.

Patented Dec. 17, 1912.

Application filed August 15, 1910. Serial No. 577,178.

To all whom it may concern:

Be it known that I, WILLARD IRVING TWOMBLY, a citizen of the United States, residing in the borough of Manhattan, in the city, county, and State of New York, have invented new and useful Improvements in Internal-Combustion Engines, of which the following is a specification.

This invention relates to internal combustion engines wherein a pair of opposed piston cylinders are connected in alinement to the crank case, and having a piston to work in a pair of opposed cylinders, the said piston being connected to the crank shaft within the working portions of the cylinder, and relates particularly to that class of engines known as the four cycle type, wherein an explosion of fuel mixture or combustible material takes place in each cylinder of the engine upon alternate revolutions of the crank shaft.

It is the primary object of the invention to provide an engine of this type which is simple, compact and light in construction, which is durable and efficient in operation, and comprising a small number of parts so arranged to be readily accessible and develop high power.

A further object of the invention is to improve and simplify the construction of the piston cylinders, comprising a combustion and ignition chamber for each cylinder having fuel intake and exhaust ports in alinement with each other with valves to operate therein, whereby to always insure a fresh supply of combustible material and the ignition of the same, and a complete exhaustion of the spent gases of combustion from the combustion chamber after an explosion has taken place.

A further object of the invention is to improve and simplify the construction and operation of the valve mechanism to control the supply of fuel to the combustion chamber and the exhaustion of the spent products of combustion therefrom comprising a pair of valves, the stem of one of which valves is slidably mounted in the stem of the other valve, and means to normally maintain both of said valves closed, the valves being alternately operated or opened by a cam on a cam shaft operated from the crank shaft, and the opening of either of said valves exerting an increased closing pressure upon the other valve.

Other objects and advantages will hereinafter appear.

In the drawings accompanying and forming a part of this specification, Figure 1 is a plan view of my improved engine with the cover of the crank case removed, the combustion chambers of the piston cylinders being shown in section as well as the exhaust outlets, and the cover or top of the fuel chamber removed. Fig. 2 is a side elevation. Fig. 3 is a sectional end elevation taken on the line A—A of Fig. 2, looking in the direction of the arrow. Fig. 4 is an enlarged sectional plan view taken on the line B—B of Fig. 2. Fig. 5 is a sectional side elevation of the piston and illustrates the manner of connecting the same to the crank shaft. Fig. 6 is a sectional end elevation of the piston taken on the line C—C of Fig. 5 looking to the right thereof. Fig. 7 is a sectional end elevation of the piston to illustrate the manner of mounting the roller bearing on the wrist pin of the crank shaft and means to automatically adjust said bearing to take up any wear or play between the piston tracks and bearing, said section being taken substantially on the line D—D of Fig. 5. Fig. 8 is a sectional plan view of the parts shown in Fig. 5 taken substantially midway thereof. Fig. 9 is an enlarged detail plan view of the valve mechanism. Fig. 10 is an enlarged sectional side elevation of the valve mechanism. Fig. 11 is a detail plan view of the cover for the crank case. Fig. 12 is a sectional end elevation of said cover taken through the line F—F, Fig. 11. Fig. 13 is a sectional end elevation of a pump to mechanically oil the operative parts of the engine, part of the crank case being shown in section to illustrate the manner of constructing the oil well therein and the connection of the pump thereto, the pump plunger being shown operatively connected to the crank shaft. Fig. 14 is an enlarged detail end elevation of the blower casing located below the crank case, the casing being partly broken away and showing a fan or blast wheel rotatively mounted therein to mechanically cool the engine. Fig. 15 is a bottom view of the casing, shown in Fig. 14, being partly broken away to illustrate the construction and mounting of the fan wheel therein, and the location of the air outlets.

Similar characters of reference designate

like parts throughout the different views of the drawings.

As a preface to a further description of my improved engine I desire to state that the same is shown as consisting of an air cooled four-cycle engine, although it will be obvious that the same may be constructed as a water or combined water and air cooled engine, and I have shown the same as comprising two pairs of opposed cylinders fixed in alinement to a crank case, and as an explosion takes place in one cylinder, one of the cylinders will be exhausting, compression of combustion material or fuel taking place in another cylinder, and the other cylinder is taking or sucking in combustible material or fuel. Furthermore the engine will work just as effectively if one pair or three or more pairs of cylinders are utilized.

In the present instance I provide a crank case 1 of rectangular or box-like construction open at the top and provided with a removable cover 2, so as to readily get access to the working parts of the engine, the said crank case also having openings in the end walls 2', 3' (which walls extend from the bottom to the top thereof) for the passage of a crank shaft 3 which is rotatively mounted therein by means of ball bearings 4.

In the construction shown the ball bearing at the right (Fig. 4) is carried in a boss 5 formed in a bracket 6, which boss engages in the said opening in the end of the crank case and secured thereto as by screws or bolts 7, the said bracket serving to support the engine as in the frame of a motor vehicle in any suitable manner. This end of the crank shaft is also provided with a thrust bearing 8, a washer 9 being interposed between said bearing and the ball bearing to retain the latter in place, and a washer 10 is secured to the boss 5 of the bracket 6 to retain the thrust bearing in place and also prevent any foreign matter, such as dust, entering the bearing. The thrust bearing is interposed between the roller bearing of the crank shaft and the hub of a fly wheel 11, which latter is fixed to the crank shaft and constructed to also form one member of a friction cone clutch to connect the engine with the driving mechanism of a motor vehicle or the like.

The roller bearing at the left hand end of the crank shaft (Fig. 4) is carried in a cup shaped bushing 12 engaging in the opening in the end wall 3' of the crank case, a washer 13, secured in place by bolts or screws 14 engaging in tapped holes in the crank case, (which bolts also serve to maintain the bushing in place,) retaining the ball bearing in place and also preventing dust and the like from entering said bearing.

Piston cylinders 15 having outwardly

projecting fins are provided with sleeve portions 16 which engage in oppositely-disposed openings 31 in the sides of the crank case and have a lap-joint connection 32 within the crank case, the said cylinders also being provided with laterally-projecting flanges 17 which abut against the sides of the case and are secured to the latter by means of bolts 18 passing through said flanges and engaging in tapped holes in the crank case. The sleeve portions of the cylinders are provided with oppositely-disposed slots 19 to permit of the passage of the crank shaft, and have a second pair of oppositely-disposed slots 20 located at right angles to the slots 19 for the passage of the wrist pin of the crank shaft during the rotation of the latter. Projecting outwardly from the cylinders are chambers 21 which are offset from the center of the cylinders and communicate with the bore thereof and constitute the combustion and valve chambers, said chambers have each a fuel inlet port 22 and an exhaust port 23 in alinement with each other. The chambers 21 of the piston cylinders have channel shaped portions projecting parallel with the cylinders to abut against the adjacent sides of the crank case and with the chambers 21 and the adjacent side walls of the crank case serve as fuel chambers 24 open at the top and having each a removable cover 25 secured in place by a strap 25' and bolts 26', said cover resting upon a laterally-projecting flange of the crank case and the top of the combustion chamber to form an entirely closed fuel chamber. The fuel intake port 22 of the combustion chamber 21 communicates with said fuel chamber 24, and a port 26 in a conduit 27 extending along the top of the side wall of the crank case also communicating with said fuel chamber. The conduit 27 has an inlet port 28 in communication with a fuel outlet port in a manifold duct or conduit 29 in the cover of the crank case, and said conduit 29 having a fuel inlet port 30 to communicate with the source of fuel supply, such as a carburetor (not shown) which may be directly fixed upon the cover of the crank case. A spark plug S is screw threaded into the combustion chambers just below the exhaust port 23 so that the spark points will project into the path of the incoming combustible material or fuel through port 22 and will always be in a fresh mixture of combustible material which will be readily fired by a spark generated by said plug.

The pistons are in the nature of double pistons, that is, they are so constructed as to operate in a pair of opposed cylinders and connected to the crank shaft within the working portions of the cylinders, and comprise a pair of releasably connected heads 33 and 34, having the usual rings 34''. The

head 33 is provided with a sleeve portion 35 cast integral with said head and having a tongue and groove connection 36 with the head 34. The sleeve portion has a pair 5 of oppositely-disposed slots 37 cut through the end thereof, the other end extending somewhat into the piston head proper 33, the free end registering with a recessed or cut-out portion 38 in the head 34, said opening 10 permitting of the slipping of the piston onto the crank shaft 3 and the reciprocation of the piston transversely to the axis of the crank shaft, and also prevents rotation of the piston. The sleeve portion 35 is 15 also provided with a second pair of oppositely-disposed slots or openings 39 which are substantially at right angles to the openings 37 to permit of rotary movement of the wrist of the crank shaft within the piston 20 through its orbit of movement which in the present instance is greater than the diameter of the piston. The piston heads are recessed, as at 33', 34', said recesses with the inner faces of the end walls of the piston 25 cylinders 15 form compression chambers.

Adjustably secured within the sleeve portion 35 with the ends engaging in the slots 39 are a pair of tracks 40 to engage at opposite sides of the wrist pin of the crank shaft, 30 the said tracks near their outer ends abutting against inwardly-projecting lugs 41 on the sleeve portion, and secured in place by tie-rods or bolts 42 screw threaded into the backs of said tracks and locked in place by 35 means of jam nuts 43, washers 44 being interposed between said lock-nuts 43 and tracks, the ends of which engage between the lugs 41 to prevent sliding or endwise displacement of the tracks. The bolts pass 40 through the piston heads and are engaged outside thereof by jam nuts 44' to draw the backs of the tracks up against the lugs 41 and lock them rigidly in position. The faces 45 of the tracks are inclined or beveled, a beveled roller bearing on the wrist pin 46 of the crank shaft having a rolling engagement with said faces and constituting the connection between the piston and the crank shaft. The roller bearing on the wrist pin 50 consists of a ring 47 having an internal and external bevel, comprising substantially a cone shaped ring. The wrist pin 46 of the crank shaft is also tapered or beveled the inclination of which is opposite to the inclination of the inner surface of the ring, and tapered rollers 48 carried by an inclined or tapered carrier 49 interposed between the wrist pin and the ring 47.

Passing through openings in the crank-shaft wrist at opposite sides of the roller bearing are a pair of springs 50, 51, and maintained in said openings by set screws 52, the free ends of which springs are bow shaped. The ends of the spring 51 bear

against the ring 47 at opposite sides of the 65 wrist pin, and the ends of the spring 50 likewise bear against the roller carrier 49, to exert a pressure the reverse of the pressure of the spring 51 to automatically adjust said roller bearing to take up any play 70 or wear between the wrist of the crank shaft and the piston tracks.

For the purpose of controlling the supply of fuel mixture to the combustion chamber 21 and the exhaust of the spent products 75 of combustion from said chamber, I provide suitable valve mechanism comprising a valve 55 seated in the inlet port 22 for the control of the fuel intake, the stem of said valve being hollow and at the end provided with a lock 80 nut 69. Slidably mounted in a bushing 57 screw threaded into the side wall of the crank case is a tappet or cam follower 56 in the form of a tubular member, one end of which abuts against the nut 69 and the other 85 end projecting into the crank case, the said tappet 56 having an oil hole 58 for the purpose of supplying lubricant to the interior thereof. The nut 69 also serves as a means to adjust the stem of the fuel valve to compensate for wear or regrinding of said valve 90 or its seat.

An exhaust valve 55' is seated in the port 23 oppositely to the valve 55 the stem 59 of which is slidably mounted in the stem of the 95 fuel-intake valve, and the tappet 56, with its free end screw threaded into a laterally-projecting portion 60 of one arm of a yoke member 61, the said end also having a saw-cut 62 therein and a set screw 63 engaging 100 in a tapped hole passing through the saw-cut portion of the stem to draw the same together and lock the valve stem 59 in engagement with the yoke arm 60. The other arm of the yoke 61 also has a laterally-projecting portion 64 slidably mounted in a bushing 65 in the opposite wall of the crank case. The screw threaded engagement of the valve stem 59 with the yoke 61 also serves as a means to adjust the exhaust valve to 110 compensate for wear or regrinding of the valve or its seat.

The fuel-intake and exhaust valves are normally maintained closed or seated in the ports 22, 23 by means of a spring 66, coiled 115 about the stem of the fuel-intake valve and confined between the projecting ends of a key 67 passing through a slot in the stem of the exhaust valve and slidable in a slot 68 in the stem of the fuel-intake valve. The 120 other end of the spring is seated in a cup-shaped locking nut 69 in screw threaded engagement with the stem of the fuel valve. This nut 69 is provided with a saw cut 70, a screw 71 passing through that portion of 125 the nut in which the saw cut is located, to draw the nut firmly together and prevent accidental rotation of the nut on the valve.

stem. The nut 69 also serves to adjust the spring 66 to increase or decrease the tension thereof.

To open the exhaust valve I provide a cam 5 72 on a cam shaft 73 journaled in bearing or pillow blocks 72' in the end walls 2' and 3' of the crank case and also in a rib extending across the top of said case by means of suitable bearings 74, and maintained therein by 10 caps 73' secured by screws engaging in the tapped holes 74'. The said cam during its rotation engages with a wheel or roller 75 rotatively carried by the portion 64 of the yoke 61 and thereby forcing the valve 55' 15 away from its seat against the tension of the spring 66. A pair of cams 76 located on the cam shaft opposite the cam 72 engage with a hardened collar or ring 77 on the end of the tappet 56, which tappet abuts against 20 the nut 69 on the stem of the fuel-intake valve 55 causing the said valve to slide on the stem of the exhaust valve to force it away from its seat in the port 22 against the tension of the spring 66 and open the 25 same.

For the purpose of readily removing the fuel-intake and exhaust valves, I construct the seat for the exhaust valve in a bushing 78 screw threaded into the combustion 30 chamber 21 and in which bushing a manifold pipe 79 engages for the purpose of leading off the spent products of combustion. It will be noted that the fuel chamber 24 also is in the nature of a valve chamber through 35 which the stems of the valves pass. To remove the valves it is only necessary to remove the bushing 78, the screw 63 is then released when the exhaust valve may be freely rotated to disconnect it out of screw threaded engagement with the projection 60 of the yoke 61 when the valves may be pulled out through the opening in which the bushing 78 engages. To remove the exhaust 40 valve the nut 69 is released to decrease the tension of the spring 66 when the key 67 is slipped through the slot in the stem 59 and the exhaust valve stem drawn out from the fuel valve stem. It will be noted that as one of the valves is opened by its cam or 45 cams, the opening movement of such valve will compress the spring 66 and thereby exert an increased closing pressure on the other valve.

The cam shaft 73 is operated by the crank shaft 3, a gear 80 fixed on the cam shaft meshing with a gear 81 on the crank shaft 3, the ratio between the gearing being two to one; that is, two revolutions of the crank shaft will transmit one revolution to the cam shaft, and the cams 72, 76 are so located on the cam shaft and timed to alternately open the exhaust and fuel-intake valves.

In an engine constructed as shown in the drawings with two pairs of opposed cylinders in alinement, the cams for the different

cylinders are so timed that when an explosion takes place in one cylinder, upon a further rotation of the crank shaft of approximately 180 degrees or one half of a revolution, the valves in one of the combustion 70 chambers of the piston cylinders will be closed and a compression of combustible material or fuel taking place therein, while in another chamber the exhaust valve will be opened and the spent products of combustion being forced out, and in the other chamber the fuel-intake valve will be opened and the piston sucking or taking in a fresh charge of fuel or explosive mixture. 75

As already stated, the valves of a cylinder at one side of the crank shaft are slightly offset from, or arranged out of line with, the valves of its opposed cylinder, but in a plane parallel with the axis of the cylinders, (Fig. 1,) this construction permitting of the locating of the cylinders in alinement and the proper locating of the cams on the cam shaft so that each of the valves will be positively operated by an independent cam or cams. 80

For the purpose of mechanically supplying lubricant to the working parts of the engine I provide in the bottom of the crank case 1, preferably cast integral therewith, an oil well 85 into which extends a pump 95 chamber, (designated in a general way by H), said chamber having laterally-projecting flanges whereby it is supported in the bottom of the crank case and secured thereto by screws 86. The pump chamber is provided with a central bore 87 in the bottom of which is screw threaded a plug 88 having an inlet 89 communicating with the central bore 87, the lower end of said inlet being countersunk or beveled and the inner end constructed to form a seat for a ball 89'. Branching out from the bore 87 are a pair of outlets 90, which may be formed by drilling in from the side of the pump chamber, and then closing the outer end of said drill 100 hole by means of a plug 91. A pair of ducts 92, parallel with the central bore 87, communicate at their lower ends with the branches 90 from the central bore 87, balls 93 being seated in the elbow formed by the 105 ducts 90, 92 and maintained in their seats by springs 94 confined between said balls and plugs 95 screwed into the upper ends of said ducts. Branching out from the upper ends of said ducts 92 are outlets 96 to which are connected by means of unions or couplings 97, ducts 98 leading up through the crank case and along the top of the side walls thereof, the said ducts 98 being provided with outlet nipples or spouts 99 at a 110 point over the top of the cams on the cam shaft. (Fig. 3.)

A reciprocating plunger or piston 100 engages in the central bore 87 of the pump chamber and at its outer end is pivotedly 115 120 125 130

connected, as at 101, to one of a pair of connected straps 102, encircling a cam or eccentric disk 103, and which may form a part of the gear 81, fixed to the cam shaft, as by means of a key 104, engaging and rotating in said straps 102, and as the crank shaft revolves reciprocating the plunger 100. At the top of the pump chamber the plunger may be provided with suitable packing 105, 10 in the present instance shown as confined between a boss 106 at the top of the pump chamber and a cap 107 having a screw threaded engagement with the boss 106.

To regulate the flow of the oil I provide a 15 needle valve 108 having a knurled head and having screw threaded engagement with a tapped hole 109 in the bottom of the oil well. The hole 109 is counterbored for a portion of its length, and has seated therein a plug 20 110 through which the needle valve also passes, suitable packing 111 being provided for said valve and confined between the plug 110 and the bottom of the counterbore to prevent the oozing out or dripping of lubricant from the oil well. By removing the 25 needle valve 108 and plug 110 all of the oil may be readily drained from the oil well. As the crank shaft rotates the eccentric disk 103 rotating in the straps 102 causes the piston 100 to reciprocate each revolution of the crank shaft imparting one reciprocation to the piston. During the upward stroke of the piston the sucking action will draw the ball 89 away from its seat and suck the oil 30 35 from the oil well through the opening in the plug 88, and as the piston descends the ball 89 is again seated and the oil sucked in during the upward stroke of the piston is forced out through the branches 90 unseating the balls 93 against the tension of the springs 94, through the outlets 96, and the ducts 98 to the outlets or spouts 99 from whence it drips onto the cams, pistons and the crank-shaft bearings to lubricate the same, the oil 40 45 draining into the bottom of the crank case from whence it flows into the oil well to be again utilized. Owing to the great velocity at which the crank shaft is revolved, and the consequent rapid reciprocation of the pump 50 55 plunger, there will be a steady stream of lubricant supplied, the volume of which may be regulated by the needle valve 108 in the bottom of the oil well by screwing it in or out to increase or decrease the extent of the opening in the plug 88.

To mechanically air cool the engine, I provide at the bottom of the crank case a casing (designated in a general way by I) which may be cast integral with the crank 60 case, the top of said casing I forming the bottom of the crank case. Said casing in the present instance is substantially rectangular in shape and conforming to the shape of the crank case and attached piston 65 cylinders. The casing is provided with a

central opening 112 in the bottom thereof, and a pair of openings 113 at the top and below the piston cylinders. Fixed to a stud or spindle 114 rotatively mounted in a pair of bosses 115, 115 in said casing, the axis of which is transverse to axis of the crank shaft is a fan or blast wheel, (designated in a general way by J). The lower boss 115 is supported by a spider 116 forming a part of the bottom of the casing. These bearings 70 75 are of a well known type comprising a cup-shaped member 117 seated in the bosses, and beveled collars 118 on the spindle 114, the said cup and collar constituting a raceway for a series of balls 119. In the present instance the lower collar has a screw threaded engagement with the stud 114 for the purpose of adjusting the bearing, and locked in place by a jam nut 120. Fixed on said stud 114 is a beveled pinion 121 meshing 80 85 with a beveled gear 122 fixed on the crank shaft, the gear 122 in the present instance consisting of a pair of releasable segments to facilitate the placing of the same upon the crank shaft, and have mating lugs 123 in 90 which engage bolts 124 for the purpose of securing the segments together.

The blast or fan wheel J comprises a series of circumferentially disposed spoon shaped blades or vanes 125 fixed at their 95 ends, as by means of rivets, to a pair of annular side plates 126, 126. The said fan wheel is secured to the spindle 114 as by means of a set screw 127 passing through a hub 128 from which radiate spokes or arms 100 129 fixed at their outer ends to one of the vanes or blades 125. As the engine is operated the fan is caused to rotate by means of the meshing gears 121, 122, the centrifugal action of the fan wheel sucking or drawing air through the opening 112 and forcing it through the outlets 113, where it is directed up around the ends and sides of the piston cylinders and between the cylinder fins by means of deflectors 130 fixed to the fan 105 110 casing and projecting upwardly around the sides and ends of the cylinders. (Figs. 3, 4, 14, and 15.) The deflectors lie close to the outer edges of the cylinder fins and as the fan casing is so proportioned that one end projects to some extent beyond the sides of the piston cylinders the deflectors 130 are curved inwardly as clearly shown in Fig. 14 at 131.

The left hand end of the crank case (Fig. 4) is constructed with a compartment or chamber separate from the crank case proper, consisting of the end wall 3', the projecting ends of the side walls, and an end wall 3'', the driving gears for the cam shaft as well as the oil pump mechanism being located therein. An opening 4' between the lower end of the wall 3' and the bottom of the crank case permitting the flow 115 120 125 130 of the oil from the crank case into the oil

well. The wall 3" has an opening 5' for the inserting of a crank (not shown) to engage in the end of the crank shaft to manually crank the engine.

5 The operation of my improved engine is substantially as follows: As already stated, for the purpose of illustration, I have shown in the present instance only two pairs of opposed cylinders 15 in which the explosions 10 take place in the order indicated by a, b, c and d. Assuming the pistons to be in the position shown in Fig. 4 with compressed fuel or combustible material in the cylinder a with the fuel intake and exhaust valves 15 closed, an explosion having just taken place in the cylinder d, a fresh charge of combustible material or fuel drawn in the cylinder b, and the spent products of combustion exhausting from the cylinder c. As an 20 explosion takes place in the cylinder a; the spent products of combustion are forced out from the cylinder d, fuel compressed in cylinder b, and a fresh charge of fuel drawn into cylinder c. Upon further rotation of 25 the crank shaft approximately 180 degrees or one half of a revolution an explosion takes place in cylinder b, fuel compressed in cylinder c, a fresh charge of fuel drawn into cylinder d, and the spent products of combustion exhausted from the cylinders a; during 30 the next one half revolution of the crank shaft an explosion takes place in cylinder c, fuel compressed in cylinder d, fresh fuel drawn into cylinder a, and the cylinder 35 b is exhausting. During a still further rotation of the crank shaft one half of a revolution an explosion takes place in the cylinder d, fuel compressed in cylinder a, fresh fuel drawn into cylinder b, and the cylinder 40 c is exhausting, when the cycle of operations is repeated.

From the foregoing description it will be noted that one explosion takes place in each cylinder during one cycle of operations or 45 during two revolutions of the crank shaft.

Variations may be resorted to within the scope of my invention.

Having thus described my invention, I claim:

50 1. In an internal combustion engine, the combination with a crank case and a crank shaft journaled therein, of a cylinder fixed to said case provided with a combustion chamber having fuel-intake and exhaust 55 ports with valve seats therein, the valve seat of one port being opposite to the valve seat of the other port; a valve seated in the fuel-intake port to control the charge of fuel to the cylinder; a valve seated in the exhaust 60 port to control the exhaust from the cylinder, the stem of said exhaust valve passing through the fuel-intake valve and its stem, whereby the latter valve is slidably supported on the stem of the exhaust valve; a 65 spring coiled about the stem of the fuel-

intake valve; an abutment on the stem of the fuel-intake valve; a key passing through the stem of the exhaust valve with the ends projecting through slots in the stem of the intake valve; said spring confined between 70 the said abutment and key to normally maintain both valves seated; a cam shaft journaled in the crank case; and cams on said shaft so arranged as to alternately open the fuel-intake and exhaust valves; the opening 75 of one said valves causing the spring to exert an increased closing pressure on the other valve.

2. In an internal combustion engine, the combination with a crank case and a crank shaft journaled therein, of a cylinder fixed thereto having aligned fuel-intake and exhaust ports; oppositely seated valves in said ports to control the charge of fuel to and the exhaust from the cylinder, one of said valves and its stem mounted upon the stem of the other valve; a spring coiled about the outer valve stem; an adjustable abutment on the outer valve stem; a key passing through the inner valve stem with the ends projecting 85 through slots in the outer valve stem; said spring confined between said abutment and key to normally maintain the valves seated; and said abutment being adjustable to increase or decrease the tension of the spring; 90 a tappet in the crank case in which the inner valve stem is slidably supported; a cam shaft driven from the crank shaft; and cams on said shaft arranged to engage with the inner valve stem and the tappet to unseat 100 the valves.

3. In an internal combustion engine, the combination with a crank case and a crank shaft journaled therein, of a cylinder fixed to said case having a combustion chamber 105 with aligned fuel-intake and exhaust ports; a valve for the fuel-intake port; a valve for the exhaust port seated oppositely to the intake valve, the stem of which exhaust valve passes through the fuel-intake valve and its 110 stem; a spring coiled about the stem of the fuel intake valve; a key passing transversely through the exhaust-valve stem with the projecting ends passing through slots in the fuel-intake valve stem; an adjustable nut on the end of the fuel-intake valve stem; said 115 spring confined between said key and nut and tensioned to normally maintain both valves closed; a cam shaft journaled in the crank case and driven from the crank shaft; 120 and cams on said shaft to operate the valves.

4. In an internal combustion engine, the combination with a crank case and a crank shaft journaled therein, of a cylinder fixed to said case having a combustion chamber 125 with aligned fuel-intake and exhaust ports; a valve for the fuel-intake port; a valve for the exhaust port seated oppositely to the intake valve, the stem of which exhaust valve passes through the fuel-intake valve and its 130

stem; a spring coiled about the stem of the fuel-intake valve; a key passing transversely through the exhaust-valve stem with the projecting ends passing through slots in the fuel-intake valve stem; an adjustable nut on the end of the fuel-intake valve stem; said spring confined between said key and nut and tensioned to normally maintain both valves closed; a tubular tappet slidably mounted in the crank case with one end abutting against the end of the fuel-intake valve stem and in which the stem of the exhaust valve is also slidably mounted; a cam shaft journaled in the crank case and driven from the crank shaft; and cams on said shaft to operate the valves.

5. In an internal combustion engine, the combination with a crank case and a crank shaft journaled therein, of a cylinder fixed to said case having a combustion chamber with alined fuel-intake and exhaust ports; a valve for the fuel-intake port; a valve for the exhaust port seated oppositely to the intake valve, the stem of which exhaust valve 20 passes through the fuel-intake valve and its stem; a spring coiled about the stem of the fuel-intake valve; a key passing transversely through the exhaust-valve stem with the projecting ends passing through slots in the fuel-intake valve stem; an adjustable nut on the end of the fuel-intake valve stem; said spring confined between said key and nut and tensioned to normally maintain both valves closed; a cam follower in the form of 25 a tubular tappet slidably mounted in the crank case coaxial with the stem of the fuel intake valve and in which the stem of the exhaust valve also slidably engages; a slidably mounted yoke shaped member releasably connected to the exhaust-valve stem; a roller carried by said yoke member; a cam shaft journaled in the crank case and driven from the crank shaft; and cams on said shaft to engage with the yoke roller and the tappet so timed to alternately open the valves.

6. In an internal combustion engine, the combination with a crank case and a crank shaft journaled therein, of a cylinder fixed to said case having a combustion chamber with alined fuel-intake and exhaust ports; a valve for the fuel-intake port; a valve for the exhaust port seated oppositely to the intake valve, the stem of which exhaust valve 50 passes through the fuel-intake valve and its stem; a spring coiled about the stem of the fuel-intake valve; a key passing transversely through the exhaust-valve stem with the projecting ends passing through slots in the fuel-intake valve stem; an adjustable nut on the end of the fuel-intake valve stem; said spring confined between said key and nut and tensioned to normally maintain both valves closed; a tubular tappet slidably 55 mounted in the crank case coaxial with the

fuel-intake valve stem and in which the stem of the exhaust valve is slidably mounted; a yoke-shaped member having laterally-projecting portions, one of which is slidably supported in the crank case, the other slidably supported in the tappet and having a screw threaded engagement with the end of the exhaust-valve stem; a roller carried by said yoke member; a cam shaft journaled in the crank case and driven from the crank shaft; a cam on said shaft to engage with the yoke roller to open the exhaust valve; cams on said shaft at opposite sides of the exhaust-valve operating-cam to engage with the tappet to open the fuel-intake valve; the opening of one valve causing the valve-seating spring to exert an increased closing pressure on the other valve.

7. In an internal combustion engine, the combination with a crank case and a crank shaft journaled therein, of a cylinder fixed to said case having a combustion chamber with alined fuel-intake and exhaust ports; a valve for the fuel-intake port; a valve for the exhaust port seated oppositely to the intake valve, the stem of which exhaust valve passes through the fuel-intake valve and its stem; a spring coiled about the stem of the fuel-intake valve; a key passing transversely through the exhaust-valve stem with the projecting ends passing through slots in the fuel-intake valve stem; an adjustable nut on the end of the fuel-intake valve stem; said spring confined between said key and nut and tensioned to normally maintain both valves closed; a tubular tappet slidably mounted in the crank case with one end abutting against the fuel-intake valve stem and in which the stem of the exhaust valve also slidably engages; a yoke-shaped member having laterally-projecting portions, one of which is slidably supported in the crank case, the other slidably supported in the tappet and having a screw threaded engagement with the end of the exhaust-valve stem; a roller carried by said yoke member; a cam shaft journaled in the crank case and driven from the crank shaft; a cam on said shaft to engage with the yoke roller to open the exhaust valve; cams on said shaft at opposite sides of the exhaust-valve operating-cam to engage with the tappet to open the fuel-intake valve; the opening of one valve causing the valve-seating spring to exert an increased closing pressure on the other valve; said nut on the end of the fuel-intake valve stem serving to adjust said valve to compensate for wear or grinding of said valve or its seat, and the screw threaded engagement of the exhaust-valve stem with the yoke member serving to adjust said valve to compensate for wear or grinding of said valve or its seat.

8. In an internal combustion engine, the combination with a crank case and a crank

shaft journaled therein, of a cylinder fixed to said case having a combustion and valve chamber in an integral part thereof with aligned fuel-intake and exhaust ports; a valve for the fuel-intake port; a valve for the exhaust port seated oppositely to the intake valve, the stem of which exhaust valve passes through the fuel-intake valve and its stem; a spring coiled about the stem of the fuel-intake valve; a key passing transversely through the exhaust-valve stem with the projecting ends passing through slots in the fuel-intake valve stem and against which key one end of the spring abuts; an adjustable lock nut on the end of the fuel-intake valve stem against which the other end of the spring abuts; said spring tensioned to normally maintain both valves closed; a cam follower in the form of a tubular tappet one end abutting against the nut on the end of the fuel-intake valve stem, and the other end projecting into the crank case, the stem of the exhaust valve also slidably engaging in said tappet; a bushing in the crank case in which said tappet is slidably mounted; a yoke shaped member having laterally projecting portions, one of which is slidably support-

ed in the tappet and having a screw threaded connection with the stem of the exhaust valve; a bushing in the crank case in which the other projecting portion of the yoke is slidably mounted; a roller carried by said yoke member; a cam shaft journaled in the crank case and driven from the crank shaft; a cam on said shaft to engage with the yoke roller to open the exhaust valve; cams on said shafts at opposite sides of the exhaust-valve operating-cam to engage with the tappet to open the fuel-intake valve; the opening of one valve causing the valve-seating spring to exert an increased closing pressure on the other valve; said nut on the end of the fuel-intake valve stem serving to adjust said valve to compensate for wear or grinding of said valve or its seat.

WILLARD IRVING TWOMBLY.
